UNITED STATES PATENT OFFICE.

CHRISTIAN SCHNEIDER, OF BRITTON, SOUTH DAKOTA.

RAIL JOINT.

Application filed July 14, 1924. Serial No. 725,886.

This invention relates to a new and improved rail joint and has for an object the provision of novel means whereby two rail sections are joined together by an overlapping joint so designed as to prevent the friction and accidents that at present accompany the usual design of rails.

Other objects of the invention are to eliminate the usual noise in the present rails as the wheels of moving cars pass over the joints; to prevent the flattening of the wheels as they cross these joints; to prevent the rails from spreading in case the spikes are loosened; to provide a joint to be held in place by any standard fish-plates; and to provide, also, a joint of such construction and design as to give a continuous tread and a full weight rail throughout.

Additional objects and advantages of the invention will be apparent from the following description and from an inspection of the accompanying drawing, wherein:

Figure 1 is a perspective of the interlocking sections of a rail joint constructed in accordance with the invention, the sections being shown apart.

Figure 2 is a side view of the rail joint, with the sections placed end to end and held securely by standard fish-plates.

Figure 3 is a top plan view of the improved rail joint showing the parts in position, as when joined together.

In describing the invention in detail reference is had to the drawing which forms a part of this specification and wherein like numerals of reference indicate like parts throughout the several views.

In constructing the joint, the head of rail section A is cut away on each side to leave an extended flange 1 projecting beyond the shoulders 2 and 3 and supported by the web 4 and base 5, both of which are of full weight, thus securing an unusually strong end to the rail and being weakened in no

way. Flange 1 is integral with and forms a vertical prolongation of web 4, being equal in width to the latter and having its side and end faces in vertical alignment with the corresponding faces of the web and having its upper surface lying flush with the upper face of the rail section. Rail section B has the end portions of its web 6 and base 7 cut away to leave the head projecting to a distance substantially equal to the length of the extended flange 1 of rail section A and the projecting part of the head is bifurcated,

as at 8, to provide longitudinal and parallel projecting arms 9 and 10 which fit snugly against opposite sides of flange 1 in line with shoulders 2 and 3. Arms 9 and 10 are preferably 3 inches long and the head of rail section A is cut away on each side for a distance of 3 inches to allow room for the said arms when the two rails are placed end to end. However, in extreme and severe cases of climatic expansion and contraction, the arms and cut-away may be made 4 inches, if necessary. In a 4 inch rail, the inside shoulder 2 on the head of rail section A may, if desired be made 1½ inches, the webs 4 and 6 being made 1½ inches and the outside shoulder 3 being made 1 inch and these dimensions may vary accordingly in the larger and smaller rails, thus making a reasonable allowance on the inside of the rail where there is the greater weight and friction. Otherwise, the web is placed in the center of the rail head and base.

This rail joint is designed to be held in place by any of the standard fish-plates so necessary for the proper alignment and reinforcement of any rail joint should any extra strains be thrust upon the joint or unexpected break occur. As will be seen in Figure 2, the rails A and B of the present invention are adapted to be strengthened and held securely in place by 2 fish-plates 11 bolted on either side of the joint. It will, moreover, be seen that this joint is so designed that it gives a firm interlocking union: the rail sections A and B being so united as to constitute practically one continuous rail and an unbroken smooth surface, and being so arranged that while allowing for proper longitudinal expansion and contraction they are, when in position, secured against any lateral and vertical movement or displacement in relation to each other.

Another distinct feature of this rail joint is the ease with which repairs may be made. The one rail section where the two meet in the joint may be easily lifted, after the fish-plate has been removed, and another similar rail section placed in its stead, and yet at all times both rail sections are held from all lateral movement by the interlocking joint, and when the fish-plates are in place the ends of both rail sections are thus held from all lateral and vertical movement.

In practical fields the details of construction may necessitate alteration and it is,

therefore, to be understood that the invention is not to be considered as limited to the precise construction herein described but that all such changes, modifications, and alterations required may be resorted to as being within the scope of what is claimed.

Having thus described the invention what is claimed, is:

A rail joint comprising abutting rail sections each having a base, web and head, one rail section having opposite side portions of its head cut away to leave an extended flange integral with and forming a vertical prolongation of the web, said flange being equal

in thickness to the said web and having its ¹⁵ side and end faces in vertical alignment with the corresponding faces of the web and its upper surface lying flush with the upper face of the section, the other rail section having the end portions of its base and web cut ²⁰ away to leave the head projecting to a distance substantially equal to the length of the said extended flange and having the projecting part of the said head bifurcated vertically to engage opposite sides of the said ²⁵ flange.

In testimony whereof I affix my signature.
CHRISTIAN SCHNEIDER.
